PORTABLE TOILET BUILDING

Logan W. Johnson, Minnetonka, Minn., assignor to
Satellite Service Company, Minneapolis, Minn., a corporation of Minnesota

Filed July 3, 1969, Ser. No. 18,046

Term of patent 7 years

Int. Cl. D25—04

U.S. Cl. D13—1

FIG. 1 is a front elevational view of a portable toilet building embodying my design;

FIG. 2 is a rear elevational view of said portable toilet building;

FIG. 3 is a right side elevational view of said portable toilet building, the left side view being substantially a mirror image thereof;

FIG. 4 is a plan view of said portable toilet building;

FIG. 5 is a fragmentary cross-sectional view taken substantially along line 5—5 of FIG. 4 to show the center rib structure;

FIG. 6 is a fragmentary cross-sectional view of a second embodiment of said rib structure;

FIG. 7 is a fragmentary cross-sectional view of a third embodiment of said rib structure;

FIG. 8 is a fragmentary cross-sectional view of a fourth embodiment of said rib structure; and

FIG. 9 is a fragmentary cross-sectional view of a fifth

The bottom of the portable toilet building of my design is free of ornamentation.

I claim:

The ornamental design for a portable toilet building, as shown and described.
